J. H. CARVER,
GEAR, ROLL, AND THE LIKE,
APPLICATION FILED JULY 18, 1918.

1,340,011.

Patented May 11, 1920.

Inventor,
James H. Carver,
by *Albert S. Davis*
His Attorney.

UNITED STATES PATENT OFFICE.

JAMES H. CARVER, OF SCHENECTADY, NEW YORK, ASSIGNOR TO GENERAL ELECTRIC COMPANY, A CORPORATION OF NEW YORK.

GEAR, ROLL, AND THE LIKE.

Specification of Letters Patent. Patented May 11, 1920.

1,340,011.

Application filed July 18, 1918. Serial No. 245,480.

To all whom it may concern:

Be it known that I, JAMES H. CARVER, a citizen of the United States, residing at Schenectady, in the county of Schenectady, State of New York, have invented certain new and useful Improvements in Gears, Rolls, and the like, of which the following is a specification.

The present invention relates to gears, 10 rolls and the like which are made of a compressible material, forming a compressible element, held between metallic holders or shroudings. The compressible material may be, for example, spinnable textile fibers, raw- 15 hide, cloth or the like.

The object of my invention is to provide an improved metallic holder for gears, rolls and the like of this general type which can be readily applied to the compressible element to hold it under compression and which will be very strong and rugged.

For a consideration of what I believe to be novel and my invention, attention is directed to the accompanying description and 25 the claims appended thereto.

In the present instance, I have shown my invention as applied to a gear wheel, the compressible material of which is formed of spinnable textile fiber, as this is a material 30 to which I have found my holder well adapted, but it will be understood, of course, that it is not limited thereto.

In the drawing, Figure 1 is a sectional view of a gearing embodying my invention; Fig. 2 is an end elevation partly in section thereof; Fig. 3 is a view similar to Fig. 1 showing an arrangement for closing the joint between the two parts or members of a holder; Figs. 4 and 5 are fragmentary 40 sectional views of another form of joint; and Fig. 6 is a top plan view of a portion of a gear wheel.

Referring to the drawing, 10 indicates a compressible element forming the main portion of the gear wheel rim. It is supported 45 in a holder comprising two cylindrical members 11 and 12 having annular flanges 13 and 14 respectively. The cylindrical members 11 and 12 are located inside the compressible element and have their meeting 50 edges suitably fastened together, and the annular flanges 13 and 14 hold between them the compressible element 10. I preferably 55 employ a type of connection between the meeting edges of the members 11 and 12

which draws the flanges 13 and 14 firmly into engagement with the element 10 and which is not likely to give or loosen. In Figs. 1, 2 and 3 I have shown an arrangement wherein the member 12 is formed with 60 an undercut annular groove 15 into which a wedge-shaped tongue 16 fits. The tongue 16 is bent inwardly a little as shown in Fig. 3 to permit it to slip over the edge of groove 15 and it is then forced into the 65 groove by a suitable tool as indicated at 17. The inclined surfaces of the tongue and groove serve to draw the two members of the holder together and bring the flanges 13 and 14 into firm engagement with the 70 element 10.

In Figs. 4 and 5 is shown a modified form of connection wherein the member 12 is provided with an undercut annular groove 18 having a recess 19 at its bottom which provides an annular lip or rim 20 which is 75 rolled down over the tongue 21 after such tongue has been forced into groove 18 and recess 19 as shown in Fig. 5.

In a device of this character, the compressible element exerts considerable pressure against the flanges in an axial direction and it is very important that the holder be so constructed as to withstand such pressure and resist bending of the flanges. This 80 result is accomplished to a high degree in my improved structure because of the fact that the flanges 13 and 14 are integral parts of the members 11 and 12 and also because of the fact that said flanges are inclined 85 toward each other from their bases radially outward. Since flanges 13 and 14 are integral with members 11 and 12 each of the two members of which the holder is formed is an angle iron and hence very strong, and due to 90 the inclined structure of the flanges 13 and 14 they will withstand a greater axial force 95 for a given thickness than they would if straight. Furthermore this inclined arrangement gives a dove-tailed connection between the flanges and the compressible element 10 so that it is strongly anchored 100 against centrifugal force.

To prevent the element 10 from turning relative to the holder, the inner sides of 105 flanges 13 and 14 may for some purposes be provided with suitable notches or grooves as indicated at 22, which bite into the sides of the element 10. (See Fig. 6.) It will 110 be understood that in the case of a gear

wheel the teeth are cut after a blank has been formed in the manner described, such teeth being indicated at 23. In other cases, a blank formed as described may be finished 5 as is necessary or desirable.

With the above described arrangement, the holder comprises only two principal parts or members which may be readily and cheaply made by forging or drawing. The 10 joint between them occurs at a point where it is subjected to axial pulling stresses only, there being little if any bending stresses thereon. Furthermore, the arrangement avoids a joint located at or near either of 15 the flanges 13 or 14 and as a result both these flanges are of equal strength to withstand the stresses to which they are subjected. The result is a holder which has a maximum of strength for a given weight.

20 In accordance with the provisions of the patent statutes, I have described the principle of operation of my invention, together with the apparatus which I now consider to represent the best embodiment thereof, 25 but I desire to have it understood that the apparatus shown is only illustrative, and that the invention can be carried out by other means.

What I claim as new and desire to secure 30 by Letters Patent of the United States, is:—

1. In an apparatus of the character described, the combination of an annular body element of compressible material, a holder comprising two parts which are located 35 within the bore of said element with their edges meeting therein, said parts having flanges which engage said body element, and an annular tongue and groove connection between said meeting edges, said tongue and 40 groove having inclined engaging surfaces which serve to draw the parts of the holder together when the same is being assembled.

2. In an apparatus of the character described, the combination of an annular body element of compressible material, and a holder comprising two parts which are located 45 within the bore of said element with their meeting edges therein, said parts having flanges which are inclined toward each other from their bases radially outward and 50 engage said body element, said meeting edges being provided with annular, inclined, complementary grooves forming annular tongues which interlock to hold the flanges against said body element. 55

3. In an apparatus of the character described, the combination of an annular body element of compressible material, and a holder therefor comprising two annular parts which are located within the bore of 60 said element with their edges meeting therein, and flanges on said parts between which said body element is held, said meeting edges being provided with annular, inclined, complementary grooves forming annular 65 tongues which interlock to hold the flanges against said body element.

4. In an apparatus of the character described, the combination of an annular body element of compressible material, a holder 70 therefor comprising two annular parts which are located within the bore of said element with their edges meeting therein, flanges on said parts between which said body element is held, one of said meeting 75 edges being provided with an annular, undercut groove and the other with an inclined tongue, which fits into said groove to lock the holder parts together.

In witness whereof I have hereunto set 80 my hand this 17th day of July, 1918.

JAMES H. CARVER.
